(57) **CLAIM**

The ornamental design for a lock plate and handle trimset assembly, as shown and described.

DESCRIPTION

FIG. 1 is a front elevational view of a lock plate and handle trimset assembly showing our new design;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a bottom plan view thereof.

The broken lines of the door indicate an environment. Other broken lines indicate unclaimed portions of the design. None of the broken lines form part of the claimed design.
